UNITED STATES PATENT OFFICE.

EDWIN J. MYERS, OF TOPPENISH, WASHINGTON.

METALLIC TIE AND RAIL-FASTENER.

1,099,265.

Specification of Letters Patent.

Patented June 9, 1914.

Application filed April 3, 1914. Serial No. 829,223.

To all whom it may concern:

Be it known that I, EDWIN J. MYERS, citizen of the United States, residing at Toppenish, in the county of Yakima and 5 State of Washington, have invented certain new and useful Improvements in Metallic Ties and Rail-Fasteners, of which the following is a specification.

This invention relates to improvements 10 in metallic railway ties and rail fastening devices used in connection therewith; and it consists in the novel construction, combination and arrangement of parts herein-after fully described and claimed.

15 The primary object of the invention is to provide a simple, strong and effective means for quickly clamping track rails to the metallic tie which is of such construction that it will be effectively locked to the track 20 rails and will tend to prevent longitudinal and transverse shifting of them.

The above and other objects are attained in the construction illustrated in the accompanying drawings in which:

25 Figure 1 is a cross section through a pair of track rails showing one form of my improved tie and rail fastening device, in side elevation; Fig. 2 is a top plan view of the same; Fig. 3 is a vertical section 30 taken on line 3—3 of Fig. 2; Figs. 4 and 5 are vertical sections taken on lines 4—4 and 5—5 respectively of Fig. 3; Fig. 6 is a perspective view of the metallic tie; and Fig. 7 is a perspective view of one of the 35 clamp members.

Referring more particularly to the drawing, 1 denotes the body of my metallic tie which is of concavo convex shape in cross section, its concave side being turned down- 40 wardly so that the angular lower edges 2 of the tie will embed themselves in the ballast or road bed and the tie will consequently be effectively retained in position. The convex upper side of the tie body has formed 45 at suitable distances from its ends, flat seats 3 for the track rails 4. At one or both ends of the tie there may be formed lips 5 which overlie the outer edges of the seats 3 so as to engage the outer base flanges of the 50 track rails but in the embodiment illustrated, the lip 5 is formed only on the right hand end of the tie. In connection with the lip 5 on said end is shown a tie clamping member 6 and on the other or left hand 55 end of the tie is shown two of such mem-

bers 6, two being used when the lip 5 is omitted. Each of these clamping members 6 consists of a curved or concave body having a thickened or reinforced central portion 7 on its bottom face and from the center of which projects a hook-shaped lug 8 having a beveled end 9. The body portion of the clamp member 6 has its depending edges or flanges 10 formed with transversed alined openings 11 as clearly shown in Fig. 65 7. The bodies of the clamp members 6 are adapted to fit in correspondingly shaped seats 12 formed on the upper side of the tie on one or both ends of the rail seats 3 and when the clamp members 6 are in position, their thickened portions 7 rest on flat 70 seats 13 in which are formed sockets 14 to receive the hook-shaped lugs 8. Transverse openings 15 intersect the sockets 14 and contain bolts, pins or similar members 16 75 with which the hook-shaped lugs 8 engage as clearly shown in Fig. 3. Transverse openings 17 pierce the body of the tie and are adapted to aline with the openings 11 in the clamp members 6 so that when the latter are in position, bolts or similar removable fasteners 18 may be passed through such alined openings as seen in Fig. 4 to retain the clamp member in position. The clamp members 6 have their inner ends, that 80 is, their ends nearest the track rails, formed with overhanging lips 19 which engage the base flanges of the rails 4 to securely retain them on the seats 3.

In use, the track rails 4 when being fastened to the tie are placed on the seats 3 and their outer flanges engaged with the lips 5 when the latter are used. The clamp members 6 are then dropped into place and their hooks 8 hooked under the bolts or pins 95 16, and when their bodies drop into the seats 12 so that the openings 11, 17 aline, the bolts 18 are placed in position to effectively retain all parts in firm engagement with each other. Any time it is necessary to remove the track rails, the bolts 18 may be removed and the clamp plate 6 unhooked from the pins or bolts 16.

From the foregoing description taken in connection with the accompanying drawings, the construction and operation of the invention will be readily understood without requiring a more extended explanation.

Various changes in form, proportion and the minor details of construction may be re- 110

sorted to without departing from the principle or sacrificing any of the advantages of the claimed invention.

I claim as my invention:

- 5 1. The combination of a metallic cross tie having a flat track rail seat, a second seat adjacent the track rail seat and formed with a socket, said tie also having a transverse opening adjacent said socket, a transverse 10 pin intersecting the socket, a rail clamping plate to enter said second seat and formed with a depending hook-shaped lug to enter said socket and engage said pin, and a removable fastening passed through said 15 transverse opening and said clamp member.
2. The combination of a metallic cross tie of concavo-convex shape in cross section and formed on its convex upper side with a flat rail engaging seat, said upper side being 20 also formed with an adjacently disposed seat to receive a clamp member, said second seat having a centrally arranged socket, said tie being also formed adjacent said socket with a transverse opening, a transverse pin to 25 said socket, a rail clamping member shaped to fit said second seat and formed between its ends with a hook-shaped lug to enter said socket and engage said pin, one end of said clamp member having a projecting lip to 30 engage the track rail and its other end being

formed with openings to align with said transverse opening in the tie, and a removable fastening passed through said aligned openings.

3. The combination of a metallic cross tie 35 of concavo-convex shape in cross section having formed on its upper convex side a flat rail engaging seat and additional seats formed on each side of the latter and including centrally arranged sockets, said tie 40 being also formed with transverse openings adjacent the sockets, transverse pins in said sockets adjacent the rail seat, clamp members to fit the second mentioned seats and formed with depending hook-shaped lugs to 45 enter said sockets and engage the pins therein, said members being formed at one end with projecting rail engaging lips and at their opposite ends with openings to align with said transverse openings in the tie, and 50 removable fastenings in said aligned openings.

In testimony wherof I have affixed my signature in presence of witnesses.

EDWIN J. MYERS.
